Primary Examiner — Darcey E Gottschalk*(74) Attorney, Agent, or Firm* — AP Patents**CLAIM**

The ornamental design for a cap, as shown and described.

DESCRIPTION

FIG. 1 illustrates a perspective environmental view of a cap; FIG. 2 illustrates another perspective environmental view of the cap of FIG. 1 with a protective lid in an open position; FIG. 3 illustrates a top view of the cap in FIG. 1; FIG. 4 illustrates a top view of the cap in FIG. 2; FIG. 5 illustrates a bottom view of the cap in FIG. 1; FIG. 6 illustrates a front elevation view of the cap in FIG. 1; FIG. 7 illustrates a right elevation view of the cap in FIG. 1; FIG. 8 illustrates a left side elevation view of the cap in FIG. 1; FIG. 9 illustrates a rear elevation view of the cap in FIG. 1; and, FIG. 10 illustrates a rear elevation view of the cap in FIG. 1.

In the drawings, the broken lines show portions of a cap that form no part of the claim.
